UNITED STATES PATENT OFFICE.

MICHAEL S. COLE, OF NEW YORK, N. Y.

DRESS-SKIRT ATTACHMENT.

1,233,030.

Specification of Letters Patent. Patented July 10, 1917.

Application filed November 6, 1914. Serial No. 870,668.

To all whom it may concern:

Be it known that I, MICHAEL S. COLE, a citizen of the United States, residing at New York, in the county of New York and State of New York, have invented new and useful Improvements in Dress-Skirt Attachments, of which the following is a specification.

This invention relates to an attachment for dress skirts, its object being to provide a device which may be applied to a belt about the waistband of a dress skirt, whereby suitable means may be employed for holding the lower edge of the skirt elevated or for supporting a chatelaine, pocket book or other article from the device.

A further object of the invention is to provide an article of the character described which is simple of construction, may be made as ornamental as desired in appearance, and conveniently applied and removed.

The invention consists of the features of construction, combination and arrangement of parts herein fully described and claimed, reference being had to the accompanying drawing in which:—

Figure 1 is an outer elevational view showing the application of the invention.

Fig. 2 is an inner elevational view of the belt, showing the device applied.

Fig. 3 is a vertical section through the device.

Fig. 4 is a rear perspective view showing the spring arms of the clamp released and swung outwardly to disengaging position.

The device comprises a supporting member 1 formed from metal, and designed to be fastened to an outside belt 2 outside the waist band 3 of a dress skirt by means of a spring clamp 4, preferably formed of spring wire. This clamp 4 is approximately U-shaped or bail-shaped and comprises a pair of spring arms 5 connected at one end by a cross piece 6, said arms having at their free ends inturned locking portions 7. The cross portion 6 of the clamp extends through and is pivotally mounted in a tubular knuckle 8 formed upon or secured to the plate member 1, while the inturned locking portions 7 are adapted to engage the opposite ends of a tubular keeper member 9 also formed upon or secured to said member 1.

If desired, the keeper member 9 may be in the form of independent keepers, as will be readily understood. It will be seen from the foregoing that the arms 5 are adapted to engage and clamp the belt 2 against the member 1, whereby the member 1 is detachably secured to the belt against any possibility of displacement. By their spring action the arms 5 may be spread to release the locking portions 7 from the keeper 9, allowing the clamp to be swung outwardly to a releasing position, as illustrated in Fig. 4, so that the device may be removed from the belt.

The device may be employed for supporting a chatelaine, pocket book, or skirt lifting or supporting element. To this end I provide a suspension member 10 which is mounted upon the member 1 for swinging movement, preferably by employing a pin or rivet 11 which is passed through the member 10 into the member 1. The member 10 carries a snap stud or socket 12 to receive a snap socket or stud 13 on the article to be suspended from the member 10. This article may be a chatelaine, pocket book, or a skirt supporting element. In the present instance I have shown a skirt supporting tape or strip 14 provided at its lower end with a clasp or fastening member 15 to engage the skirt, by which the lower edge of the skirt may be held elevated to the desired extent, as will be readily understood.

What is claimed is:—

A device of the character described comprising a supporting member, a tubular keeper member upon the rear portion thereof, a tubular knuckle upon the supporting member above the keeper, a bail-shaped spring wire clamp having its cross portion pivotally engaging said knuckle and having its spring arms converging in a direction toward the keeper and provided with inturned projections to enter the opposite ends thereof, and means for connecting said supporting member with an element to be supported thereby.

In testimony whereof I affix my signature in presence of two witnesses.

MICHAEL S. COLE.
